CLAIM

The ornamental design for a therapeutic thermal pack, as shown and described.

DESCRIPTION

FIG. 1 is a top plan view of a therapeutic thermal pack showing my new design, the bottom view being a mirror image thereof;

FIG. 2 is a left side elevational view, the right side elevational view being a mirror image thereof;

FIG. 3 is a front elevational view, the rear elevational view being a mirror image thereof;

FIG. 4 is a top perspective view thereof; and,

FIG. 5 is a front perspective view thereof.
